UNITED STATES PATENT OFFICE.

FRED STARR, OF SAN FRANCISCO, CALIFORNIA.

WAVE-MOTOR.

No. 840,460.

Specification of Letters Patent.

Patented Jan. 1, 1907.

Application filed February 8, 1906, Serial No. 300,184.

To all whom it may concern.

Be it known that I, FRED STARR, a citizen of the United States, residing at San Francisco, in the county of San Francisco and State of California, have invented certain new and useful Improvements in Wave-Motors, of which the following is a specification.

My invention relates to wave-motors, and more particularly to such devices in which the motion is transmitted from a float to power-transmitting mechanism through one or more reciprocatory members connected with the float. In constructing such motors it is desirable that the float to be effective should be of large area and of considerable tonnage; but during a storm when the power and force of the waves are very great the float is liable to damage itself. Such liability to damage can be prevented by changing the position of the float, so that it is no longer exposed to the direct action or full force of the waves. This can be done by raising it above them or sinking it below them; but owing to the weight of the float it is better to submerge it. I therefore prefer to either wholly or partially sink or submerge it, which I do by increasing its weight. It can be constructed as a hollow barge adapted to receive water ballast. As the wave agitation is superficial and quickly decreases downwardly, it is evident that by sinking the float to a greater or less extent the force of the waves may be utilized to the desired extent without the danger of damage, as above indicated, or by sinking the float to the bottom it will remain substantially stationary.

An embodiment of my invention is shown in the accompanying drawings, in which—

Figure 1 is a side elevation of the wave-motor. Fig. 2 is a horizontal section on the line 2 2 in Fig. 1. Fig. 3 is a detail view of one of the guides, showing cross-head and transmissions in side elevation. Fig. 4 is a horizontal section of the cross-head and guides. Fig. 5 is a detail view showing manner of winding the transmission-cable around the drums. Fig. 6 is a detail view of the clutch arrangement in the power-drum. Fig. 7 is a vertical section of the same. Fig. 8 is a detail view of the cable adjusting and fastening device. Fig. 9 is an end elevation of the same. Fig. 10 is a diagrammatical view showing mode of anchoring the barge.

In the drawings, 1 indicates a pier, which may be of any suitable construction and located at any point in a body of water in which there is sufficient wave movement to be utilized for generating power. Anchored below the pier in any suitable manner is a float 2, which is preferably hollow and kept in the desired position by any suitable connectors, as guy ropes or cables 3. The cables preferably run over rollers 4, and those at each end extend laterally in opposite directions, so as to obstruct lateral movement and give greater stability to the float, and those at the sides preferably extend laterally longitudinally of the float in opposite directions, so as to cross each other, and thereby secure a greater length of cable to permit of the greatest vertical movement while obstructing the longitudinal movement of the float.

Located upon the pier in position to be connected with and operated by the float is the power-transmitting mechanism, which is preferably made in duplicate, and therefore the description of one will be sufficient for both. Sliding between two vertical guideways 5 is a head 6, which is connected with the float by a stem or rod 7 and pitman 8, the connection at both ends of the pitman consisting of a universal joint 9, which will permit of movement of the float in all directions, but will only transmit vertical movements to the head 6 through the stem 7.

To cause the stem to always move in a straight line, it is passed through a guide-block 10, which is mounted between the guideways 5 and is preferably seated in an opening in the pier, as indicated by the dotted lines 1 2 in Fig. 3. The guide-block, as well as the head, is preferably provided with anti-friction-rollers 13, which engage with the ways 5, as they are moved vertically therebetween. The block is loosely seated in the opening 12, so that in case of the float being raised above its usual movement the joint 9 between the stem 7 and the pitman will engage with the block and lift it off its seat or out of the opening and carry it up between the guides 5, and thereby prevent injury to any of the parts from excessive movement from the waves. As such waves recede the float falls to its normal position and the block again seats itself, the opening and the lower portion of the block being slightly inclined for insuring that result. To secure the nec-

essary rigidity of the ways 5, they are braced by a frame 14 at their upper ends and by diagonal braces 15, and each guideway is also further braced by the rods 16, which pass over struts 17 on the sides of the ways. Turnbuckles 18 are provided for placing as many of the rods and braces under tension as may be desired.

The ends of the head 6 are each preferably 10 shouldered and provided with antifriction devices, such as rollers 19, for engaging with the sides of the guideways, and they are also provided with arms or extensions 20, to each of which is connected the ends of a cable 21. 15 The intermediate portion of each cable is passed over idle pulleys 22 and 23 at the top and bottom, respectively, of the guideways and wrapped around the shell or drum portion of a clutch 24. The ends of the cable 20 are preferably connected with a suitable 25 tightener, which is shown as comprising a drum or wheel 25, journaled in the arm 20 and having pins 25' in its sides for the ends of the cable and having its periphery formed into a worm-gearing with which a worm 26 engages, said worm being adapted to be rotated in any suitable manner, as by a hand-wheel 27.

The clutch comprises a cylindrical body 28, 30 having inclined recesses 29 formed in its periphery longitudinally of the body, a shell or drum 30 surrounding the body and a roller 31 in each recess, which is adapted to be engaged by the shell, except when it is seated 35 or in the pocket or deepest portion of its recess. The body is rigidly mounted upon a shaft 32, which is provided with a power-transmitting member, as the band wheel or pulley 33. A removable wear-plate 34 is 40 preferably secured on the flat portion of each recess to receive the pressure from the roller and which plate can be replaced at any time, and thereby add to the durability or life of the clutch. A steel ring 35 is also preferably 45 inserted within the drum or casing 30 for the same purpose.

Actual use has shown that where a strain or pressure from a float weighing thousands of pounds is abruptly and repeatedly placed 50 upon the clutch members, whereby the rollers are forced into the gradually-tapering recesses between the body and the casing the contacting surfaces are quickly dented to such an extent that the clutch fails to act satisfactorily at all times, thereby requiring a renewal of the contacting surfaces, which is done more cheaply and quickly with the wear-plates than with solid members.

The shell 30 is preferably formed with one 6c of its ends, as 36, removable and adapted to be secured in position by any suitable means, as screws 37. The periphery of the drum is preferably grooved spirally, as shown at 38, and is long enough to receive several turns or 65 coils of the cable 21 and yet leave sufficient

room for the travel or lateral movement of the cable as it is wound upon the drum from one direction or the other. The shaft 32 is journaled in a bracket 39, which is secured to one of the guideways 5 in any suitable manner and at any suitable height and at one side of the path or travel of the arm 20. There are two cables connected with each head and two clutches adapted to be operated by the cables, and the inclinations of the 70 recesses in the body portions of the two clutches are arranged in opposite directions, so that one clutch operates only when the head is moving in one direction and its casing runs free when the head is moving in the 75 other direction, and the other clutch operates in the same manner, but during the movements of the head in the opposite directions, whereby one or the other of the clutches is always being operated by the reciprocation 80 of the head while the casing of the other one is running free.

Journaled in suitable supports 40 at a suitable distance from each set of guideways—four ways being shown in each set in the 85 drawings—is a crank-shaft 41, which is adapted to actuate the pistons in one or more cylinders 42, three cylinders or air-pumps being shown for each shaft. The cylinders are utilized for compressing air, which may be 90 used for any purpose, such as for actuating or driving any suitable mechanism, which, however, is not shown, as it forms no part of this invention, and the crank-shaft and cylinders are only shown to illustrate one means 95 for utilizing the reciprocatory motion of the head and the rotary motion of the clutches actuated thereby. A pulley or belt-wheel 43 is secured upon each end of the crank-shafts 41, and a power-transmitter, as a belt or rope 100 44, passes over each wheel and its corresponding wheel 33 upon the end of the crank-shaft.

As above described, my wave-motor is adapted for ordinary use—that is, with the 105 water in its normal condition; but in case a storm should arise or it should be desirable to submerge the float at any time suitable openings, as sea-cocks 45, (shown only in dotted lines in Fig. 1,) are opened, and water is admitted to the interior until the buoyancy of the float is counterbalanced to the desired extent and the float passes partly or wholly under the waves, as the case may be. During this submergence or lowering of the float 110 the heads between the guideways upon the pier are drawn down a corresponding distance, which will only cause the rope connected therewith to assume a new position upon the clutch-casing nearer one end or the other, but without changing or affecting its mode of operation in the least. In case the float should have any vertical movement while it is submerged, which it will have to a greater or less extent, depending upon the 115 120 125 130

amount of submergence, it will be transmitted to the clutches through the pitman and stems in the same manner as heretofore described.

5 When it is desired to raise the float to the surface of the water, as at the cessation of the storm, the water may be removed from it in any suitable manner; but I prefer to utilize compressed air—as, for instance, a portion of that which has been compressed by the machine itself. For this purpose a flexible conduit or hose 46 is connected with one of the cylinders or air-pumps 42 and extends down to one or more cylinders 47 on the float, two such cylinders being shown in the drawings. A valved pipe 48 extends from one end of one of the cylinders into the interior of the float, so that by opening the valve 49 in said pipe the air from one or both of said cylinders passes into the float and forces the water out through the short pipe 50, that extends from near the bottom of the float up through the top of the float in position to discharge the water back to the place from whence it was taken. The hose or pipe 46 is provided with an ordinary check-valve (not shown) to prevent the return of the air after it has been forced into the tanks or cylinders, and it communicates with both tanks 30 through communicating branches, which also permits of the passage of the air from one cylinder to the other when the water is being expelled from the float.

After the float has been raised to the surface the valve 49 is closed, and the air from the tanks is permitted to pass into a tank or cylinder 51 through connecting-pipes 52 and a valve 53. A piston 54 is mounted in the cylinder 51, and its piston-rod 55 is mounted 40 in a bearing 56 and connected with the forward guy-ropes 3 by means of a cross-piece 57. A trip 58 is mounted on the rod 55 in position for operating the valve 53 to open the said valve when the float is forced to the rear by the wave action and to close the valve when the float returns to its normal position. In this manner when the float starts to the rear the valve is opened, which will permit compressed air from the cylinders 47 50 to enter the forward end of the cylinder 51 between its head and the piston, and thereby have a tendency to stop the rearward movement of the float and force it forward into its normal position. With the forward movement of the float the valve is closed and the passage of air into the cylinder 51 is stopped.

The sidewise movements of the float are controlled so as to not place too great an abrupt strain upon the side guy-ropes by forming a cushion of air in cylinders 59, which are placed crosswise of the float at or near its ends. Rods 60 pass through these cylinders and have their ends mounted in bearings 61 and connected with the side ropes 3 in any 65 suitable manner. Piston-heads 62 are con-

nected with these rods, and when they are in their normal position the head stands substantially midway of the length of the cylinder. As the float moves laterally in either direction, it is cushioned by the air between 70 said head and that end of the cylinder.

As above described, the motor is located where there is sufficient wave motion to actuate the float, and suitable means are provided for storing or converting the energy of 75 the waves into whatever form of energy it is desired to utilize. As soon as the float is placed in position and the proper connectors made the movements of the float, whether they be great or small, regular or irregular, 80 will be transmitted to the power-generator on the pier and transformed into energy that can be utilized in a regular and uniform manner, as by being converted into electricity, 85 which can be transmitted to any point of application, near or remote, in the usual manner. Upon the approach of a storm the float is submerged to a point of safety without stopping its vertical movements, which can still be utilized for generating power the 90 same as when the float was riding upon the crest of the waves. For this purpose the reciprocating members are made long enough to extend from the float at all times to the pier—say seventy-five feet or even of a 95 greater length.

Having described my invention, what I claim as new, and desire to secure by Letters Patent, is—

1. In a wave-motor, a float, power-transmitting mechanism, reciprocating members from the float to said mechanism, each provided with a flexible portion, and means for submerging the float.

2. In a wave-motor, a float, power-transmitting mechanism, a reciprocating member connected at one end with said mechanism, a pitman connected with the other end of said member and with the float, and a loosely-mounted guide through which said member is adapted to be reciprocated and causing it to move in a straight line yet permitting excessive upward movement of the pitman.

3. In a wave-motor, a pier, clutches mounted thereon, each clutch comprising a recessed cylindrical body and a surrounding cylindrical casing, a wear-plate removably secured in each recess, a cylindrical wear-plate within each casing, a rotary member seated in each recess adapted to engage said wear-plates, a float beneath the pier, reciprocating members flexibly connected therewith and extending above the pier, and means for connecting said members with said clutches.

4. In a wave-motor, a pier, vertical guide-ways thereon, a head reciprocally mounted on said ways and having each end provided with an arm, two cables, each connected at its ends with one of said arms, a clutch connected with the intermediate portion of each 130

cable, power-transmitting mechanism connected with said clutch, and a float for reciprocating the head.

5. In a wave-motor, a pier, vertical guideways thereon, a head reciprocally mounted on said ways and having each end provided with an arm, a drum in each arm, means for rotating the said drums, two cables, one for each arm and having their ends connected 10 with said drums, a clutch connected with the intermediate portion of each cable, said clutch being adapted to operate, respectively, when the cables are moving in opposite directions, power-transmitting mechanism connected 15 with said clutch, and a float for reciprocating the head.

6. In a wave-motor, a pier, vertical guideways and a crank-shaft thereon, a head reciprocally mounted on the guideways and air-pumps connected with said shaft, two oppositely-operating clutches connected with said head, means for connecting the opposite ends of the shaft with said clutches, and a float for reciprocating said head.

25 7. In a wave-motor, a pier, vertical guideways thereon, two clutches mounted on opposite sides of said ways, a head reciprocally mounted on said ways and connected with said clutches so as to operate one clutch 30 when moving in one direction and the other clutch when moving in the other direction, power-transmitting mechanism connected with said clutches, and a float for operating the head.

35 8. In a wave-motor, a pier, vertical guideways thereon, two clutches mounted on opposite sides of said ways, each comprising a cylindrical body having inclined recesses formed within its periphery, a wear-plate 40 movably secured in each recess, a casing around said body, a cylindrical wear-plate therein, a rotary member seated in each recess adapted to be engaged by said wear-plates, respectively, a head reciprocally 45 mounted on said guideways, two cables connected at their ends with said head and having their intermediate portions coiled around

said casings respectively, power-transmitting mechanism connected with said clutches, and a float for operating the head.

50

9. In a wave-motor, a hollow float, cylinders thereon for compressed air, means for charging said cylinders by the movements of the float, a valved conduit leading from the cylinder to the interior of the float, and a pipe 55 extending from near the bottom of the float to and through the top thereof.

10. In a wave-motor, a float, guy-ropes connected therewith, and means for cushioning said connections by means of compressed 60 air.

11. In a wave-motor, a float, cylinders thereon, each provided with a piston and a rod, guy-ropes connected with said rods, and means for cushioning each piston on air between itself and the end of its cylinder. 65

12. In a wave-motor, a float, cylinders thereon, a piston in one of said cylinders, guy-ropes connected with the rod of said piston, means for charging the remainder of said 70 cylinders with compressed air by the movements of the float, and means for introducing said air into the first-mentioned cylinder between its end and the piston for counteracting the movement of the float to the rear. 75

13. In a wave-motor, a float, communicating cylinders thereon, a piston in one of said cylinders, guy-ropes connected with the rod of the piston, means for charging the remainder of said cylinders with compressed air by 80 the movements of the float, a valve for permitting a portion of said air to pass into the first-mentioned cylinder between its end and the piston for counteracting the seaward movement of the float, and a projection on 85 said piston-rod for actuating the valve as the float is moved longitudinally.

In testimony whereof I affix my signature, in presence of two witnesses, this 31st day of January, 1906.

FRED STARR.
